AIRPLANE PICKUP MECHANISM

Edward G. Hill, Richmond, Va., assignor to G. Tucker Smith and E. Govan Hill, both of Richmond, Va., as trustees

Application June 22, 1942, Serial No. 448,007

12 Claims. (Cl. 258—1.6)

This invention relates to airplane pick-up mechanisms, and more particularly to such a mechanism of the type wherein a catapult projects the article upon the picking up by an airplane-carried hook of a flexible loop connected to the article on the catapult.

In a mechanism of the type referred to, it has been proposed to arrange the article to be picked up on a catapult latched against movement, and to connect a flexible element, such as a shock cord, to the article, with a loop therein suspended across the tops of a pair of spaced masts. Such a mechanism has been provided with means operable upon the engagement of the portion of the loop between the masts by an airplane-carried hook to release the catapult and thus project the article, the latter being accelerated by the catapult so that it attains a speed approximating that of the airplane at the time the slack is taken up in the loop.

A loop of the character referred to is generally triangular, one point in the triangle being at the point of connection of the loop to the article and the other two points being at the tops of the respective masts. When the airplane-carried hook engages the loop and pulls it loose from the masts, an appreciable period of time elapses before the triangular loop is straightened out, and it is during the period that acceleration of the catapult takes place up to approximately the airplane speed.

It is essential in a device of this character that the interval of time referred to be relatively uniform in successive operations of the mechanism in order that the catapult may properly accelerate the load.

An important object of the present invention is to provide a novel apparatus of the character referred to having an extremely simple form of mechanically operated catapult latch release mechanism which is operative instantly upon the transmission of the initial pull of the airplane-carried hook on the suspended loop for releasing the catapult latch, thereby allowing a proper and relatively uniformly predetermined time interval during which the article will be accelerated so as to approximately equal the speed of the plane.

A further object is to provide a direct mechanical connection between the portion of the loop extending between the masts and the latch release device so that the initial pull on the suspended loop will release the latch.

A further object is to provide such a mechanism wherein all electrical control mechanisms

are eliminated and wherein the relatively heavy and cumbersome features of prior mechanical release mechanisms are eliminated.

Other objects and advantages of the invention will become apparent during the course of the following description.

In the drawings I have shown one embodiment of the invention. In this showing:

Figure 1 is a side elevation of the mechanism showing an airplane in flight thereover and about to engage the loop connected to the article.

Figure 2 is an enlarged fragmentary central vertical sectional view through the rear end of the catapult device and associated elements.

Figure 3 is an enlarged end elevation of the apparatus.

Figure 4 is a detail perspective view showing the catapult carriage and associated elements, the loop and supporting mast therefor, and the flexible latch release device.

Figure 5 is a section on line 5—5 of Figure 2.

Figure 6 is a detail perspective view of the casting for the release rod gripping mechanism, and,

Figure 7 is a detail fragmentary perspective view of a portion of the pick-up loop.

Referring to Figure 1, the numeral 10 designates an airplane below which is suspended a relatively rigid arm 11 which is adapted to be swung against the fuselage of the plane, or downwardly to the operative position shown in Figure 1 wherein the arm slopes downwardly and rearwardly. The arm 11 is provided at its lower end with a hook 12 for the purpose of picking up a load or article in a manner to be described. The hook 12 is carried by a cable running through the arm 11 into the plane and connected to a windlass whereby the load may be pulled upwardly into the plane, the fuselage of the latter being provided with a suitable door through which the load may be lifted into the plane. A cable 13 is connected to the arm 11 and has its upper end connected to suitable mechanism for pulling the arm upwardly against the plane to its inoperative position. The parts so far described form no part per se of the present invention and need not be specifically illustrated.

The catapult mechanism is indicated as a whole by the numeral 14. Such mechanism comprises elongated spaced frame members 15 each of which has an inwardly extending flange 16, and the flanges of the opposite frame members cooperate to form a trackway for the catapult carriage to be described. The catapult mechanism further comprises lower frame members 17 connected at their ends by transverse angle iron

frame members 18. The sides of the mechanism are covered by plates 19 extending from end to end of the mechanism as will be apparent. One end of the apparatus is covered by an end plate 20 which is secured to the cross member 18 and to a similar cross member 21 extending across and welded or otherwise secured to the adjacent ends of the frame members 15.

The end of the mechanism referred to is provided with a caster wheel 21' having a draft connection 22 and pivoted as at 23 to a bracket 24, and this bracket is secured to the end plate 20 and preferably also to the cross members 18 and 21. The other end of the mechanism is supported by wheels 25 (Figures 1 and 3).

A carriage indicated as a whole by the numeral 26 is provided therebeneath with a suitable structure 27 carrying pairs of wheels 28 and 29 at its forward and rear ends and at opposite sides thereof whereby the carriage is guided by the trackways 16. The carriage is adapted to support any suitable form of article, such as a container 30, and is provided with an end wall 31 which bears against the article to impart movement thereto when the catapult mechanism is released in a manner to be described.

The end wall 31 is provided with a latch 32 engageable by a hooked finger or detent 33 pivotally connected as at 34 to the upper end of a bracket arm 35. A rod 36 has its upper end connected to the finger 33 and its lower end connected to one arm 37 of a bell crank lever 38, this lever being pivoted as at 39 to a bracket 40 and having a second arm 41.

A control rod or bar 42 is connected at one end to the lever arm 41. This bar may be relatively small at its end connected to the lever arm 41 and has its rear end 43 tapered to increase in width as shown in Figure 4. A finger 44 (Figure 2) is connected to one end of a spring 45, the other end of this spring being connected as at 46 to a transverse element 47 which may be welded or otherwise secured to the upper edges of the angle iron members 17. When the spring 45 is tensioned it obviously tends to pull the bar 42 and turn the bell crank lever 38 in a clockwise direction, thus moving the rod 36 upwardly to release the finger 33.

Referring to Figures 2, 5 and 6, a cylindrical casing 48 is secured as at 49 to a cross member 50 and a clutch element 51 fits within the housing 48 and is urged downwardly by a spring 52. A rod 52' limits downward movement of the clutch element 51. The lower face 53 of the clutch member 51 slopes downwardly toward the free end of the bar 42 and contacts with a roller 54 as shown in Figure 2. This roller in turn, normally engages against the top surface of the wide end of the bar 43 and holds this bar down against a coacting clutch member 55, having its upper surface perpendicular to the axis of the housing 48. The clutch member 55, in turn, is held down against a roller 56 carried by the upper end of a lever 57. This lever is pivoted as at 58 to bearings 59 carried by the lower end of a bracket arm 60 preferably formed integral with the housing 48. The bracket arm 60 is provided with a stop member 61 engageable with the lever 57, above the pivot thereof, to limit swinging movement of the lever in a counter-clockwise direction as viewed in Figure 2 beyond the position shown in such figure. Therefore, the spring 52 will effect a gripping action between the clutch members 51 and 55 and any tendency of the bar 42 to move to the left as viewed in Figure 2 will tend

to cause the roller 54 to move down the inclined face 53 and thus more tightly clamp the roller in position against the bar 42. The housing 48 is provided with a slot 62 through which the flat portion of the bar 42 extends when the parts are in the positions shown in Figure 2.

The sides of the catapult mechanism are provided with outstanding arms 65 hinged as at 66 to be swung to positions parallel to the catapult mechanism and adapted to be hooked in extended operative positions by hook elements 67. Rods 68 are slideable in the ends of the arms 65 and are adapted to be held in adjusted positions by set screws 69.

15 The bars 68 are provided at their outer ends with sleeves 70 receiving vertically extending masts 71 having their lower ends received in sockets 72 carried by heavy mushroom bases 73. The masts may be fixed against sliding movement vertically by set screws 74 threaded through the sockets 70. The upper ends of the masts are provided with fingers 75 sharply inclined from the vertical in the direction of flight of the airplane for a purpose which will become apparent.

20 A flexible pick-up member 76 is adapted to be engaged by the airplane-carried hook 12 to pick up the article. The flexible member 76 is in the form of a loop connected to the article 30, as at 77, and adapted when in operative position, as shown in Figures 3 and 4, to form a generally triangular shape, the three sides of which are formed by a transverse member 78 extending across the masts, and downwardly and rearwardly converging sides 79 which are connected to the article 30 at the point 77, as stated. The portions of the flexible loop which are carried by the masts preferably are provided with rubber or similar thimbles 80 (Figure 7) to be frictionally held in position between the pairs of fingers 75 of the masts. The flexible loop is preferably formed of shock cord which, as is well known, is made up of a number of highly flexible rubber strings or bands enclosed in an expandable woven covering. It will be apparent however, that while the use of such a flexible loop is desirable, it is not at all essential, particularly for the picking up of lighter loads.

25 Centrally of the transverse portion 78 of the loop a non-elastic relatively light cord 81 is connected as at 82 and this may be done merely by tying the end of the cord 81 about the center of the portion 78 of the loop. The cord 81 extends downwardly and rearwardly for connection as at 83 to the lower end of the lever 87 to exert a pull on the lower end of such lever to swing it and thus release the bar 42, as will be further described.

30 The particular form of power employed for projecting the catapult carriage is of no importance. As generally illustrating one suitable means for propelling the catapult, I have shown a shock cord 84 connected as at 85 to the catapult carriage and passing forwardly around a pulley 86 (Figure 1), and thence rearwardly around the drum 87 of any suitable form of windlass. If desired, the drum 87 may be provided with a gear 88 meshing with a smaller gear 89 adapted to be turned by a hand crank or otherwise to wind the shock cord 84 on the drum to properly tension it.

35 It will be obvious that the rod 42 must be moved rearwardly to set it ready for operation and in order to provide access to the rod, one of the side plates 19 may be provided with a door 90 (Figure 1).

With the catapult carriage in position, the operator will reach through the door 90 and pull the rod 42 toward the right as viewed in Figure 2 to tension the spring 45, and such operation obviously swings the bell crank lever 38 to pull downwardly on the rod 36 and move the finger 33 to locking position. The finger 33 will thus hold the catapult carriage against movement to the left as viewed in Figure 2, whereupon the source of power for the catapult may be prepared for operation to provide a force ready to act instantaneously to project the carriage upon the releasing of the latch 33. This is done, in the case of the shock cord 84, by winding the cord on the drum 81 to place the shock cord under sufficient tension. One end of the string 81 will have been previously tied as at 83 to the lower end of the arm 57, and the other end of this cord will be tied to the transverse portion 78 of the pick-up loop, at a point which will be midway between the masts 71 when the apparatus is completely set up. The rubber thimbles 80 are now pressed between the fingers 75 of the masts, whereupon the masts are set up in the sleeves 70 and sockets 72 (Figure 1).

The apparatus is now ready for operation and when the pick-up plane approaches it will fly at such level as to cause the bar 11 (Figure 1) to strike against the loop portion 78 at a point slightly above the hook 12 and as near as possible midway of the length of the loop portion 78. The thimbles 80 being sufficiently tightly gripped between the fingers 75 as to be not too readily pulled loose and the loop being formed of shock cord which is elastic, the initial striking of the bar 11 against the loop portion 78 will cause the latter to move relatively downwardly and rearwardly into engagement with the hook 12. The hook will exert a sudden pull on the loop portion 78 adjacent the point 82 and this jerk will be transmitted through the cord 81 to swing the lever 57 in a clockwise direction as viewed in Figure 2. When the lever 57 has swung to its limit of movement, the cord 81 will relatively easily break, whereupon the hook 12 will continue to move the loop portion 78 to pull the thimbles 80 from the fingers 75, these fingers and the loop portion 79 moving inwardly toward each other while the loop portion 78 bends at the point 82 until the elements of the loop 69 assume a comparatively straight shape.

The lever 57 normally occupies a position at a slight angle to the vertical with its movement limited by the stop 61 and the downward pressure of the spring 52 serves to hold the lever 57 in the position referred to. The very slight vertical movement of the roller 56 necessary for the axis of the roller to pass across the vertical plane of the pivot point 58 is very slight and ample leverage is provided for the slight compression of the spring 52 necessary for such operation. After the roller 56 thus passes the vertical center, the lever 59 will freely turn under the force of the spring 52. The downward pressure of this spring thus will be released and the spring 45 (Figure 2) will quickly pull the bar 42 to the left (Figure 2) to release the latch finger 33 in the manner stated. Thus the catapult carriage will be released and the carriage will be projected generally in the direction of flight of the airplane.

It will be obvious that a small but appreciable time interval is required for accelerating the catapult carriage and the article 30 to a speed approximating that of the plane. The present apparatus provides a very simple and uniformly op-

erating means for allowing for such time interval. This time interval may be readily calculated in accordance with the plane speed, the inertia of the article 30 and catapult carriage, and the force applied to the carriage to tend to move it. Having ascertained such time interval with relation to movement of the plane, the cord 81 and loop 69 may be so related to each other that the same interval of time is provided between the initial jerking of the cord 81 and the point at which the loop 69 becomes relatively straight, taking into account the acceleration in the speed of the catapult carriage during such interval. By proper calculation, the article may be caused to be moving at a speed approximately equal to the ground speed of the plane at the point where all of the slack is taken up in the loop 76, and at such point the airplane will start to carry the load and will be affected solely by the force of gravity tending to move the article downwardly after it is released from the catapult. Downward forces on the airplane are reduced to a minimum by sloping the trackways 16 upwardly, at a slight angle toward the discharge end of the catapult, and by employing shock cord in making the loop 76, thereby cushioning any slight downward forces on the airplane due to any downward force of inertia incident to a slight drop in the level of the article after it has been freed from the catapult.

From the foregoing it will be apparent that the present apparatus provides an extremely simple catapult release mechanism which may be so accurately designed with relation to the pick-up loop as to provide almost exactly the time interval necessary for accelerating the load to be picked up before the slack in the pick-up loop is taken up. The release device comprising the clutch elements 51, 55, etc., requires so little force for its operation as to permit the use of a relatively light cord 81 which is easily broken after the latch mechanism has been released.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. In an airplane pick-up mechanism, a catapult having an article receiving carriage, a pick-up loop secured to an article on the carriage and arranged in open formation with a portion thereof supported in position to be engaged by an airplane-carried hook, an element operatively connected to said catapult and movable to render the catapult operative for projecting the carriage, and a flexible element directly connected between said first named element and said portion of the loop and normally maintained relatively straight whereby initial engagement of the airplane carried hook will move said first named element to render the catapult operative.

2. In an airplane pick-up mechanism, a catapult having an article receiving carriage, a flexible element connected to an article on the carriage and having a loop, means for supporting said loop in open formation with a portion thereof arranged transversely of the direction of flight of an airplane having a hook engageable with such portion of the loop, an element operatively connected to said catapult and movable to render the catapult operative to project the carriage, and a direct relatively straight-line flexible con-

nection between said element and said portion of the loop for transmitting movement to said element immediately upon engagement of the airplane-carried hook with said portion of the loop.

3. In an airplane pick-up mechanism, a catapult having an article receiving carriage, a flexible element connected to an article on the carriage and having a loop, a pair of spaced supporting members having means at their upper ends for releasably engaging said loop to support a portion thereof at an elevated position transversely of the direction of flight of an airplane having a hook engageable with such portion of the loop, an element operatively connected to said catapult and movable to render said catapult operative to project the carriage, and a direct relatively straight-line flexible connection between said element and said portion of the loop to transmit a pull to said element to move it immediately upon engagement of said portion of the loop by the airplane-carried hook.

4. In an airplane pick-up mechanism, a catapult having an article receiving carriage, a flexible element connected to an article on the carriage and having a loop, a pair of spaced vertical masts each having its upper end provided with a slot releasably engageable with said loop to hold the latter in open formation with a portion thereof extending transversely of the direction of travel of an airplane having a hook engageable with such portion of the loop, an element operatively connected to said catapult and movable to render the catapult operative to project said carriage, and a direct relatively straight-line flexible connection between said element and said portion of the loop approximately midway between said masts for transmitting movement to said element immediately upon engagement of the airplane-carried hook with said portion of the loop.

5. In an airplane pick-up mechanism, a catapult having an article receiving carriage, a flexible element connected to an article on the carriage and having a loop, a pair of spaced supports having their upper ends spaced a substantial distance above the ground and provided with slots to releasably receive said loop to support a portion thereof substantially transversely of the direction of movement of an airplane having a hook engageable with such portion of the loop, an element operatively connected to said catapult and movable to render said catapult operative for projecting the carriage, and a cord connected at one end to said element and at its opposite end to said portion of the loop approximately midway between the upper ends of said supports.

6. In an airplane pick-up mechanism, a catapult having an article receiving carriage, a flexible element connected to an article on the carriage and having a loop, a pair of spaced supports having their upper ends spaced a substantial distance above the ground and provided with slots to releasably receive said loop to support a portion thereof substantially transversely of the direction of movement of an airplane having a hook engageable with such portion of the loop, a lever, means having a portion engaged by said lever and controlled by said lever for rendering the catapult inoperative and releasable upon swinging movement of said lever for rendering the catapult operative for projecting said carriage, and a flexible element connected between said lever and said portion of the loop, said last named flexible element being normally maintained relatively straight whereby initial engagement of the air-

plane-carried hook with said portion of the loop will swing said lever.

7. In an airplane pick-up mechanism, a catapult having an article receiving carriage, a flexible element connected to an article on the carriage and having a loop, a pair of spaced supports having their upper ends spaced a substantial distance above the ground and provided with slots to releasably receive said loop to support a portion thereof substantially transversely of the direction of movement of an airplane having a hook engageable with such portion of the loop, a clutch device having connection with and controlling operation of said catapult, an element engaging and controlling said clutch device to maintain said catapult normally inoperative and movable to control said clutch device to render the catapult operative for projecting the carriage, and a flexible element normally arranged relatively straight and directly connected between said element and said portion of the loop substantially centrally of the length thereof to move said element immediately upon engagement of said portion of the loop by the airplane-carried hook.

8. In an airplane pick-up mechanism, a catapult having an article receiving carriage, a flexible element connected to an article on the carriage and having a loop, a pair of spaced supports having their upper ends spaced a substantial distance above the ground and provided with slots to releasably receive said loop to support a portion thereof substantially transversely of the direction of movement of an airplane having a hook engageable with such portion of the loop, a clutch device comprising a pair of clutch elements, a member having connection with said catapult and engageable by said clutch elements to render the catapult inoperative, a lever normally arranged in a position engaging one clutch element to maintain said clutch device effective for holding said member, said lever being movable to release said first mentioned clutch element and thus release said member from said clutch device to render the catapult effective for projecting the carriage, and a flexible element normally arranged in a relatively straight line and directly connected between said lever and said portion of the loop substantially centrally of the length thereof.

9. In an airplane pick-up mechanism, a catapult comprising a carriage, a source of power normally conditioned to tend to move said carriage, and a latch normally engaging and holding said carriage against movement, a flexible element connected to an article on the carriage and having a loop, means for supporting said loop in open formation with a portion thereof extending transversely of the direction of movement of said carriage to be engaged by a hook carried by an airplane traveling over said catapult in said direction, an element movable to release said latch, and a direct straight-line flexible connection between said element and said portion of the loop centrally of the length thereof.

10. In an airplane pick-up mechanism, a catapult comprising a carriage, a source of power normally conditioned to tend to move said carriage, and a latch normally engaging and holding said carriage against movement, a flexible element connected to an article on the carriage and having a loop, means for supporting said loop in open formation with a portion thereof extending transversely of the direction of move-

ment of said carriage to be engaged by a hook carried by an airplane traveling over said catapult in said direction, means tending to release said latch, a lever having one end operative for preventing such means from releasing the latch, and a flexible substantially straight-line connection between said lever and said portion of the loop substantially centrally of the length thereof for turning said lever immediately upon engagement of said portion of the loop by the airplane-carried hook to render said last named means operative for releasing said latch.

11. In an airplane pick-up mechanism, a catapult comprising a carriage, a source of power normally conditioned to tend to move said carriage, and a latch normally engaging and holding said carriage against movement, a flexible element having a loop, means for supporting said loop in open formation with a portion thereof extending transversely of the direction of movement of said carriage to be engaged by a hook carried by an airplane traveling over said catapult in said direction, a member operative to release said latch, a spring tending to move said member in a latch-releasing direction, a lever normally arranged in a position to prevent a latch releasing movement of said member, and a flexible substantially straight-line connection between said lever and said portion of the loop substantially centrally of the length thereof

whereby initial engagement of the airplane-carried hook with said portion of the loop will turn said lever and release said member for a latch-releasing movement.

- 5 12. In an airplane pick-up mechanism, a catapult comprising a carriage, a source of power normally conditioned to tend to move said carriage, and a latch normally engaging and holding said carriage against movement, a flexible element having a loop, means for supporting said loop in open formation with a portion thereof extending transversely of the direction of movement of said carriage to be engaged by a hook carried by an airplane traveling over said catapult in said direction, a member having mechanical connection with said latch, a spring urging said member in a latch-releasing direction, a clutch device engageable with said member to prevent a latch-releasing movement thereof, a lever engaging a portion of said clutch device to render it effective for holding said member against movement, and a flexible element connected between said lever and said portion of the loop substantially centrally of the length thereof whereby initial engagement of the airplane-carried hook will turn said lever and release said clutch device to permit said spring to move said member in a latch-releasing direction.
